DESIGN FOR AN ELECTRIC BULB

Louis Lander, St. Louis, Mo., assignor to North
American Electric Lamp Company, St. Louis,
Mo., a corporation of Missouri

Application May 3, 1934, Serial No. 51,673

Term of patent 7 years

To all whom it may concern:

Be it known that I, LOUIS LANDER, a citizen of the United States of America, residing at the city of St. Louis, State of Missouri, have invented a certain new, original, and ornamental Design for an Electric Bulb, of which the following is a specification, reference being had to the accompanying drawing, forming a part thereof.

The view is an elevation of an electric bulb showing my new design, said bulb being substantially circular in horizontal cross-sections.

I claim:

The ornamental design for an electric bulb substantially as shown and described.

LOUIS LANDER.
